UNITED STATES PATENT OFFICE

ARTHUR C. SAXE, OF COLUMBUS, AND HOMER A. SMITH, OF MANSFIELD, OHIO; SAID SMITH ASSIGNOR TO THE BARNES MANUFACTURING COMPANY, OF MANSFIELD, OHIO, A CORPORATION OF OHIO, AND SAID SAXE ASSIGNOR TO THE JAEGER MACHINE COMPANY, OF COLUMBUS, OHIO, A CORPORATION OF OHIO

SELF-PRIMING PUMPING APPARATUS

Application filed January 2, 1930. Serial No. 418,069.

This invention relates to drainage pumps and aims to provide an improved automatic or self-priming liquid pumping apparatus of the centrifugal type.

5 It will be best understood by description with reference to the attached drawings illustrating one practicable embodiment in a portable trench-pump construction.

In said drawings:

10 Fig. 1 is a perspective view of the pump as placed in operation to drain a ditch;

Fig. 2 is a longitudinal sectional view of the pump on enlarged scale and omitting the power means therefor;

15 Fig. 3 is a transverse section thereof taken on the line 3—3 of Fig. 2; and

Fig. 4 is an end elevation showing a detail of special mounting for the pump.

In the illustrative construction, a mounting base or bed is provided by parallel beams 5 of a chassis-frame shown supported on wheel-trucks for convenience in transportation and maneuver to desired position.

20 An internal combustion engine fixed on this frame and represented by the conventional hood 6 serves to drive the pump through its crank or fly-wheel shaft 7 (see Fig. 2). As this engine per se forms no part of the invention and moreover may be 25 of any generally familiar type, there is no need to describe it further.

Aligned for direct driving connection with said engine shaft is another shaft 8 extending into a casing or shell 9, and in this instance providing the rotor shaft of a centrifugal pump organization. This last-mentioned shaft is journaled in a block 10 shown coupling the engine and aforesaid pump casings rigidly together by bolting thereto and formed with an elongate bearing 11 providing medial support for said shaft. The latter has flexible coupling connection with the fly-wheel of the engine shaft, but may advantageously be connected instead through a

clutch 12 provided thereon primarily for a purpose which will presently appear.

The above-mentioned casing or shell (9) of the pump unit is cradled between the bars of the chassis-frame for support independently of the engine and coupling block. Constituting in this instance a part of a centrifugal pump organization, it is formed with an axial inlet opening 13 and a tangential outlet passage 14 common to pumps of that type. The rotor shaft extending thereinto carries a rotor-member of special design providing primary and secondary impellers 15 and 16 respectively, each having its blades working against the back wall of the casing (see Fig. 2). In this special design, said member comprises a casting with cone-shaped hub recessed to form the blades of the small or secondary impeller behind the vanes radially extended therefrom to provide the large or primary impeller. The resultant web-portions partitioning the two impellers apart have holes 17 therein to admit limited quantities of pumped liquid between the blades of the secondary impeller.

70 The pump intake is effected by suction through a hose 18 connected at the inlet opening of said casing, while the aforesaid outlet passage thereof is controlled by a check-valve 19 working in chamber 20. A hose 21 connected with the latter serves to conduct the discharge away.

Above the pump casing, a chamber 22 communicates therewith by a pipe 23 opening behind the secondary impeller (see Fig. 2). This chamber is shown partitioned into two compartments by a plate 24 having an opening 25 at its top for passage of air and an opening 26 at its bottom for passage of liquid from the one compartment to the other for equalizing purposes.

80 In the larger of said chamber's compartments, a float 27 rising and falling with liquid above a predetermined level actuates an air-admission valve 28, in this instance carried

on the guided stem of the float and normally closing upon a seat 29 provided in an extending cover 30 of the chamber. Some other form of valve might of course be equally suitable.

5 The aforesaid chamber communicates with the intake of a suction-pump 31 by pipe 32 shown connecting with the extending cover thereof below the aforesaid air-admission valve. A valve 33 is advantageously provided in this pipe for regulating the force of suction therethrough. Said suction-pump is impelled by shaft 34 journaled on a support above the coupling block and driven from the 10 aforementioned clutch by a chain 35 working over sprockets on the two. It may accordingly be thrown into and out of operation simply by engaging or disengaging the clutch. Being in this instance of the eccentric type working in oil, this suction-pump discharges into a superposed chamber 36 having baffle plates 37 therein for separating the oil from the air, which latter is expelled through spout 38 while the oil flows back thereinto. Some 15 other form of suction-pump might of course be used with equal efficiency.

20 The disclosed organization is extremely simple but highly effectual in providing an automatically operable or self-priming pumping apparatus for draining ditches and excavations. Its operation is briefly described as follows:

25 Assuming the apparatus is placed in position with the suction hose 18 extending below the level of flood water in an excavation, the engine is started to drive the rotor-member and the clutch engaged to drive the suction-pump. The check-valve 19 of the discharge line being closed, said suction-pump 30 will quickly exhaust air from the two compartments of the chamber 22 and also from the centrifugal pump casing and its suction line or hose. The suction thus created draws water up through the hose into the pump casing to prime it for operative discharge 35 through chamber 20 and hose 21 in the usual way.

40 Continuing action of the suction-pump draws part of the intake water back through the holes 17 in the rotor-member and up the pipe 23 into said chamber 22, where the liquid level will equalize in its two compartments. When the liquid level therein rises sufficiently 45 to raise the float 27, the latter will lift or open the valve 28 and admit air to the chamber, thus breaking the suction action. The water within this float chamber will then flow back through the pipe 23 under the sucking force of the pump discharge occasioned 50 by the primary impeller, until the liquid in said chamber falls to a level permitting the float to again close the valve 28.

55 This cycle of operation is continually repeated to keep the pump operably primed so long as the lower end of the intake hose 18

remains below the water level in the excavation. If there is sufficient water in the excavation to assure operation for a protracted period before its level will fall below the end of said hose, the clutch may be disengaged to save wear on the suction-pump after the main pump has first been primed and assumed normal operation; but if there is shallow water in the excavation, it is best to keep the suction-pump also in continuous operation. Should the liquid be drained to a level below the hose end, the pump action will of course cease and any water previously drawn into the chamber 22 will then flow quickly back into the pump shell under the sucking force exerted thereon by the secondary impeller throwing it radially against the shell walls, so as to hasten the closing of the valve 28 and set the pump apparatus for immediate re-priming and resumed operation when the intake hose is again submerged below the water level in the excavation.

60 A desirable cradle mounting for the pump casing 9 of the apparatus is illustrated in Fig. 4 representing a sectional end view of the chassis-frame. In this mounting the aforesaid casing is shown resting in a pair of wedge-shaped blocks 39 slidable in a cross-block 40 and movable coincidently in opposite directions by a rod 41 having opposite thread engagement therewith in this instance through lugs 42. These sliding blocks may advantageously have dovetail engagement with the cross-block, while the adjustment thereof may be facilitated by a turn-wheel 43 on the operating rod. If desired, two such rods may be used, one on either side of the blocks. By this arrangement centering the aforesaid casing between the beams of the frame, all strain upon the coupling block or rotor shaft is easily and quickly relieved simply by drawing the wedge-shaped blocks closer together to raise the casing and carry the full load thereof.

65 Various modifications may obviously be made with different changes in form and arrangement of parts without departing from the scope of this invention, and it will therefore be understood that the appended claims are not intended to limit the same to the specific construction or embodiment shown in the drawings.

70 Having thus described our invention, what we claim as new and desire to secure by Letters Patent of the United States is:

75 1. A self-priming pumping apparatus comprising in combination an engine; a rotor of a centrifugal pump unit driven by said engine and embodying a casting providing primary and secondary impellers working one behind the other against the back of an enclosing casing; a suction intake connection with said casing; a valve-controlled tangential discharge therefor; a chamber communicating with the back of the casing and hav-

ing a float-actuated valve admitting air thereto, a suction-pump driven from said rotor and connecting with said chamber for exhausting air therefrom and from the pump casing and its intake connection; and a discharge for said suction pump.

2. An automatic self-priming liquid pumping apparatus comprising in combination a power plant; a rotor of a centrifugal pump unit driven thereby and embodying co-operable primary and secondary impellers working one behind the other against the same wall of the enclosing casing; a suction intake connection with said casing; a valve-controlled tangential discharge therefor; a chamber communicating with said casing by a pipe opening thereinto behind the secondary impeller; a float-actuated valve admitting air to said chamber upon rise of liquid thereinto above a predetermined level; and a suction-pump driven also by said plant and connecting with said chamber for therethrough creating a siphonic action drawing liquid thereinto after first filling the rotor casing, the siphonic action being alternately broken and restored by operation of the aforesaid valve with rise and fall of liquid in said chamber above the predetermined level.

3. In a centrifugal pump apparatus, means for keeping the pump primed for continuous discharge operation comprising in combination, a chamber having communication with the pump casing from behind the rotor element for receiving a portion of the priming intake therefrom; a valve in said chamber admitting air thereto by operation with rise of a float above a predetermined level, and a driven suction-pump connected with said chamber for therethrough creating a siphonic action drawing liquid thereinto after first filling the rotor casing, its siphonic action being continuously broken and restored by operation of said valve with rise and fall of liquid in the chamber above the predetermined level.

4. In combination with a portable centrifugal pump with driving means, means for automatically priming and keeping the pump charged for operative discharge, said means comprising a chamber above the level of the pump-rotor shaft and having a single conduit connection with the pump casing behind its rotor element; a valve in said chamber admitting air thereto by operation with rise of a float above a predetermined level, and a driven suction-pump connected with said chamber for therethrough creating a siphonic action drawing liquid thereinto after first filling the pump rotor casing, its siphonic action being continuously broken and restored by operation of said valve with rise and fall of liquid in the chamber above the predetermined level.

5. An automatic self-priming liquid pumping apparatus comprising in combination,

an engine; a centrifugal pump unit embodying a rotor member with rotor casing having an axial intake connection and a valve-controlled tangential discharge; an air and liquid chamber fixed above the rotor shaft and having a single conduit connection with said casing opening thereinto behind the rotor member; an air-admission valve in said chamber operated by a float rising and falling with liquid above a predetermined level therein and an auxiliary suction-pump connected with said chamber for therethrough creating a strong siphonic action drawing liquid thereinto after first filling the rotor casing, the siphonic action of the last named pump being continuously broken and restored by operation of said valve with rise and fall of liquid in the chamber through said conduit above the predetermined level.

6. In combination with a centrifugal pump embodying a rotor casing and a rotor element, means operating to automatically prime and maintain the same charged for continuous operation; said means comprising an associated suction-pump communicating therewith through the medium of a chamber open to the rotor casing at a point behind said rotor element so as to therefrom receive a portion of the fluid drawn into the casing and having a float-actuated valve therein continuously operable to break the siphonic action of the suction-pump upon intake of a predetermined amount of the fluid from the rotor casing and to restore said action upon return flowage of such fluid to said casing.

7. A pumping apparatus comprising in combination, a power plant; a centrifugal pump unit embodying a rotor casing and driven rotor element; a suction-pump driven with the rotor element and communicating with said casing by a pipe line opening thereinto behind the rotor element, and a chamber disposed in said pipe line and having a float therein continuously operable with rise and fall of fluid intake to open and close an air-admission valve for alternately breaking and restoring siphonic action of the suction-pump drawing fluid thereinto from the pump casing first filled or primed thereby.

8. An apparatus according to the preceding claim 7, wherein the rotor element comprises a member formed to provide co-axial co-operable impellers partitioned apart but having their blades working against the same wall of the enclosing casing.

9. An automatically self-priming liquid-pump apparatus, comprising in combination, a driving plant; a rotor of a centrifugal pump unit driven by said plant and embodying coaxial primary and secondary impellers working cooperably one behind the other against the back wall of the enclosing casing; a suction intake connection with said casing; a valve-controlled tangential discharge therefor; a chamber communicating

with said casing by a pipe opening at its back wall close to the rotor axis and therethrough receiving a portion of the priming liquid drawn into the casing; a float-actuated valve admitting air to said chamber upon rise of liquid therein to a predetermined level; a suction pump driven also by said plant and connected with said chamber for exhausting air therefrom and from the pump casing and its intake connection to create a siphonic action therethrough; and a discharge for said suction pump.

In testimony whereof we affix our signatures.
